ROTARY BRUSH

Dyonizy Kazimierczak, Stockertown, Pa.

Application May 3, 1957, Serial No. 656,944

3 Claims. (Cl. 15—180)

This invention relates to improvements in brushes and is particularly directed to an improved and novel brush for use with a machine for treating or processing surfaces. More particularly, the present invention relates to a new rotary brush for use with a machine for applying tile mastic to a floor in the application of floor tile.

A primary object of the present invention is to provide a rotary brush, which is constructed so that a fluent material can be delivered through the brush head, as the brush rotates, for immediate and speedy application of the material to a surface.

Another important object of the present invention is to provide a rotary brush, which is adapted to be attached to a rotary shaft of a surface treating machine and which is provided with an opening, that is disposed inwardly of the bristles of the brush, for the passage of a surface treating fluent material through the brush head to the bristles.

A further important object of the present invention is to provide a rotary brush, which includes a brush head, that is circular and has an undersurface from which bristles depend, the bristles being disposed about the peripheral edge portion of the undersurface and the brush head being formed with an arcuate slot, that is disposed concentric to the center of the brush head and is arranged between the bristles and the center, such slot being provided for the delivery or passage of fluent material through the brush head to the bristles.

A still further important object of the present invention is to provide a rotary brush, which includes a brush head having an arcuate slot formed therein and arranged concentric to the center thereof and having bristles depending from its undersurface, the bristles being arranged so that the bristles, which are concentric to the slot, are of less radial thickness than the bristles, which are disposed diametrically opposite the slot, and the slot being arranged relative to the bristles so that a fluent material passing through the slot is immediately collected and spread by the bristles.

The foregoing and ancillary objects, including the provision of a sturdy, inexpensive and easily constructed brush are attained by this invention, the preferred embodiment of which is set forth in the following description and illustrated in the accompanying drawings, wherein:

Figure 1 is a view in perspective of the brush of this invention, showing the underside thereof and illustrating in particular the novel features of the slot and the relationship relative thereto of the bristles, and,

Figure 2 is a vertical, cross-sectional view, taken on line 2—2 of Figure 1.

Referring now more particularly to the accompanying drawing, the brush 10 is particularly, though not exclusively, designed for use with a machine for treating a surface, specifically, for use with a machine for applying a mastic to a floor surface, preparatory to the laying of tile on the surface. Obviously, the intended use of the brush is not to be restrictively considered, since the brush

2

may be used with any machine for the treatment of any surface and the novel features thereof will be equally well adapted for use with any type of surface-treating machine, wherein a fluent material is to be spread over a surface.

5 The brush 10 is of the rotary type and includes a circular brush head 12, which has a center opening 14. Attaching means 16 is suitably mounted in the center opening 14 and is provided for attaching the brush to the rotary shaft of a surface-treating machine, such as the machine disclosed in my co-pending application, Serial No. 656,792, filed May 3, 1957.

10 The brush head 12 includes a flat underside or undersurface 18, which is formed with pockets 20, within which the inner ends 22 of bristles 24 are socketed. It is to be noted, as shown in Figure 1, that the bristles 24 are arranged around the peripheral edge portion of the underside of the brush head and are disposed in a circular pattern, with a varying radial thickness as will be described.

15 20 The brush head 12 is formed with an arcuate slot 26, which is disposed concentric to the center opening 14 of the brush head and which terminates in curved end portions 28, the slot extending substantially 180 degrees and being formed in substantially one-half of the brush head. 25 The slot is formed vertically in the brush head and is provided for the passage of the surface-treating fluent material through the brush head to the bristles, as the brush head is rotated by the rotary shaft.

20 25 The bristles are formed in two groups, 30 and 32, as shown in Figure 1 of the drawing. The bristles of the group 30 are arranged concentric to the slot 26 and extend co-extensively with the slot, that is, from one end of the slot to the other end around the peripheral edge of the brush head. The bristles 30 are arranged in a single row and are of a similar and constant radial thickness.

30 35 The bristles of the group 32 extend from the ends 28 of the slot and are diametrically opposed to the slot and to the bristles of the group 30. The bristles at the ends of the group arrangement 32 are of slightly greater radial extent than the bristles of the group 30 and the bristles, forming the group 32, gradually increase in radial thickness, with the center portion of the group or the bristles at the center of the group 32 being of a similar radial thickness, which is considerably greater than the radial thickness of the bristles formed in the group 30.

30 35 It is to be particularly noted that, as the brush rotates, the fluent material passing through the slot 26 in the brush head will be immediately picked up by the end bristles forming the group 32 and the bristles in the group 32 will immediately serve to spread the fluent material over the surface, the bristles in the group 30 cooperating with the bristles in the group 32 to prevent the flow of the fluent material beyond the peripheral edge

40 45 portions of the brush, so that all of the material is kept within the confines of the brush and is effectively and completely spread over the surface by the brush. In use, the brush is attached to a rotary shaft of a surface-treating or processing machine by means of the attaching

40 45 means 16. As the brush rotates, the fluent material is delivered by the machine through the slot or opening 26, the delivery being timed in relation to the rotation of the brush. As the material falls through the slot 26, it is immediately gathered and spread by the end bristles of

50 55 the group 32, with the bristles of the group 30 serving to also spread the material and cooperating with the bristles of the group 32 to retain the material within the confines of the brush, so as to prevent the material from being splattered beyond the brush and so as to smoothly and

60 65 evenly spread the fluent material over the surface.

60 65 While the preferred embodiment of this invention has been described and illustrated herein, other forms may be

realized, as come within the scope of the appended claims.

What is claimed is:

1. A rotary brush for attachment to an apparatus for the application of fluent materials to a surface comprising a circular brush head having an underside, bristles depending from the underside and arranged around the peripheral edge thereof, attaching means carried by the center of the brush head for attaching the brush to a rotary shaft, said brush head having an arcuate slot formed vertically therethrough for the passage of a fluent material through the brush head in timed relation to the rotation of the brush and said slot being arranged concentric to the center of the brush head and disposed between the center and a portion of the bristles, said bristles being arranged in two groups, one of said groups being disposed concentric to and spaced outwardly from the slot and the bristles of such group being of constant and similar radial thickness and the bristles of the second group being of greater radial thickness than the bristles of the first group and the end bristles of the second group being extended inwardly of the brush head so as to lie within the same circle as the slot, whereby the end bristles confront the ends of the slot.

2. A rotary brush comprising a circular brush head having attaching means provided at its center for securing the brush to a rotary shaft, said brush head having an underside provided with a plurality of bristles, which depend therefrom and which are arranged around the peripheral edge portion thereof, said brush head having an arcuate slot formed vertically therethrough and said slot being disposed concentric to the center of the brush head, said bristles being divided into two groups, one of said groups being arranged concentric to and spaced outwardly from the slot and the other group being diametrically opposed from the slot, the bristles of the other group being of a radial extent substantially equal to the com-

bined radial extent of the bristles of the first group and the width of the slot.

3. A rotary brush for attachment to an apparatus for the application of fluent materials to a surface comprising a circular brush head having a working side and an opposing other side, bristles extending axially from the working side and arranged around the peripheral edge thereof, attaching means carried by the center of the brush head and projecting axially from the opposing other side for attachment to an operating shaft, said brush head having an arcuate slot formed therethrough and extending through the working side and the opposing other side for the passage of a fluent material from the other side through the brush head and out through the working side in timed relation to the rotation of the brush, said slot being arranged concentric to the center of the brush head and disposed between the center and a portion of the bristles, said bristles being arranged in two groups, one of said groups being disposed concentric to and spaced outwardly from the slot and the bristles of such group being of constant and similar radial thickness, the other of two groups having its bristles arranged so as to be of greater radial thickness than the bristles of the first group and the endmost bristles of the other group being extended inwardly of the brush head so as to lie within the same circles as the slot, whereby the endmost bristles of such group confront the ends of the slot.
